LUBRICATOR VALVE

Original Filed Sept. 25, 1930

UNITED STATES PATENT OFFICE

1,963,663

LUBRICATOR VALVE

Leonard R. Kerns, Battle Creek, Mich., assignor,
by mesne assignments, to The Farval Corpora-
tion, Cleveland, Ohio, a corporation of Ohio

Application September 25, 1930, Serial No. 484,333
Renewed January 10, 1934

8 Claims. (CL. 184—7)

The present invention pertains to a novel lubricator valve and consists of improvements in the devices disclosed in the copending applications of Leonard R. Kerns, Serial No. 341,960, filed February 23, 1929 and Serial No. 363,536, filed May 16, 1929.

These valves operate on the dual pressure system and comprise a measuring chamber having intake and discharge passages controlled by a valve. The valve in turn is actuated by the charging or filling pressure to open the intake passage and obstruct the discharge passage and is shifted by pressure on the measured charge to open the discharge passage and obstruct the intake passage. During or preliminary to this shift, there is a possibility that some of the measured charge placed under pressure will be forced through the intake port back into the feeding line before the valve moves to close this port, and to this extent 20 the measured quantity designed to be delivered may be smaller than actually intended.

The principal object of the present invention is to overcome this difficulty and is accomplished essentially by the provision of a check valve in the intake passage leading to the measuring chamber. The valve is so constructed as to close instantly when pressure is applied upon the measured charge or in fact to maintain a closed position except when subjected to charging or filling pressure.

The invention is fully disclosed by way of example in the following description and in the accompanying drawing, in which—

Figure 1 is a sectional view of the valve in discharged position and prior to being filled;

Fig. 2 is an elevation partly in section, showing the position of parts during filling;

Fig. 3 is a similar view showing the position of parts during discharge;

Fig. 4 is a similar view of a modified construction in loading position;

Fig. 5 is a detail section of the check valve of Figures 1, 2 and 3; and

Fig. 6 is a detail section of the main valve.

Reference to these views will now be made by use of like characters which are employed to designate corresponding parts throughout.

The valve shown in Figures 1, 2 and 3 comprises a body 1 having its upper end open and equipped with a cap or fitting 2 having an aperture 3 for connection to a pressure line as will presently appear. In the valve body is formed a main or measuring chamber 4 of cylindrical formation lengthwise of the body, and beneath this chamber is a smaller valve chamber 5 lying trans-

versely of the main chamber. The chambers are separated by a partition 6 formed with an intake port 7 and a pressure opening 8 connecting the chambers.

The chamber 5 is obviously drilled from one of the walls of the body and is there closed by a plug 9. Before applying the plug, a part 10 of an outlet passage is drilled in the blind end of the valve chamber but not entirely through the wall of the body. The principal outlet is a tapped hole 11 in the bottom of the body and adapted for attachment to a bearing or other part to receive a measured quantity of fluid in a manner already well known in the art. In order to connect the outlet to the passage 10, a hole 12 is drilled from the bottom of the body to the port 10, and another hole 13 is drilled from the outlet 11 to the hole 12. The outer end of the hole 12 is then closed by a screw plug 14.

In the valve chamber is mounted a valve consisting of two parts or cup-shaped piston sections 15 and 16. The former, as shown in Figure 6, has a reduced end 17 carrying a fiber washer 18 adapted to seat against and close the port 10. The reduced portion is of such length that the larger portion is prevented from covering the pressure opening 8 for a purpose which will presently appear. The other part 16 is formed with a stud 19 adapted in one position to engage a stop pin 20 extending inwardly from the plug 9. The part 16 is adapted to control the fluid communication between the port 7 and the intake 21 formed near the plug. Between the valve sections is a compressed spring 22 which tends to move the valve parts to their respective closing positions shown in Figure 1 but which also permits the valve parts to selectively uncover the ports controlled thereby.

In the port 7 is slidably mounted a check valve consisting of a movable member 23 having a sliding and non-obstructing fit in the port and carrying a suitable fiber washer 24 adapted to close a reduced lower end 7' of the port. A metal cup 25 is pressed into the upper end of the port and has a central aperture 26 formed by striking down a number of tongues or lugs 27 which prevent the member 23 from closing the aperture.

In the operation of the device, assuming that the parts are in the position shown in Figure 1, the valve is charged by forcing fluid under pressure into the intake 21. The pressure moves the valve section 16 to the position shown in Figure 2 where it opens the intake port 7 to the inlet 21. The normal action of the spring 22 is to hold the section 15 closed against the outlet port 10 and this action is augmented considerably by

the compression of the spring on forcing the fluid against the section 16, so that the outlet is positively and firmly closed during the loading operation. The charging pressure obviously lifts the 5 valve member 23, so that the charging fluid may flow into the port 7', around the member 23, beneath the cup 25, through the port 26, and into the measuring chamber 4 beneath a piston 28 10 slidable in the chamber. The filling process continues until the piston 28 reaches its upper limit, and the valve is now ready to be discharged.

In order to discharge the valve, pressure is relieved at the inlet 21 and applied to the opening 3. The relief of pressure at the inlet 21 permits the 15 spring 22 to move the valve section 16 to stop pin 20 where it obstructs the intake port 7 with respect to the inlet. This obstruction, however, is more definitely assured by pressure exerted upon the measured charge through the medium of 20 the piston 28 exposed to the opening 3, whereupon the valve member 23 is instantly moved downward to close the port 7'. The return of any portion of the measured charge to the intake during the discharging operation is thus definitely and positively avoided.

The pressure upon the measured charge is obviously communicated through the pressure opening 8 and against the larger portion of the valve section 15, whereupon this section is moved to the 30 position shown in Figure 3 where it uncovers the outlet port 10. The measured fluid then travels under pressure through the ports 12 and 13 to the final outlet 11. When the pressure in the opening 3 is relieved the spring 22 returns the 35 valve section 15 to the port 10, as shown in Figure 1, wherein the device is in position to take another charge.

In the modification shown in Figure 4, a somewhat different type of valve is used. A solid 40 valve member 30 without springs is adapted in one position to obstruct the discharge port 10 and open the intake port 7 and in another position to obstruct the intake port and open the discharge port. In both styles of valve, it will be seen that, 45 by reason of the direct abutment of one end against the discharge port, the sealing of this port increases with the loading pressure.

Although specific embodiments of the invention have been illustrated and described it will be 50 understood that various alterations in the details of construction may be made without departing from the scope of the invention, as indicated by the appended claims.

What I claim is:—

- 55 1. In a measuring valve, a body formed to provide a measuring chamber and a valve chamber with a partition therebetween, said partition having an intake port connecting said chambers, intake means to said valve chamber and outlet means from said measuring chamber, a two-part valve 60 slideable in said valve chamber by pressures in said intake means and measuring chamber and having one part controlling said outlet means and the other part controlling said intake port, a spring between said parts tending normally to move them to closing position, and a check valve mounted in said port and adapted to close in the direction from the measuring chamber to the valve chamber.
- 70 2. In a measuring valve, a body formed to provide a measuring chamber and a valve chamber with a partition therebetween, said partition having an intake port connecting said chambers, intake means to said valve chamber and outlet means from said measuring chamber, a two-part 75

valve slideable in said valve chamber by pressures in said intake means and measuring chamber and having one part controlling said outlet means and the other part controlling said intake port, a spring between said parts tending normally to move them to closing position, and a check valve mounted in said port and adapted to close in the direction from the measuring chamber to the valve chamber, said partition having a pressure opening connecting said chambers, said valve being disposed between said opening and intake means whereby it is moved respectively in opposite directions by the pressures in said opening and intake means.

3. In a measuring valve, a body formed to provide a measuring chamber and a valve chamber with a partition therebetween, said partition having an intake port and a pressure opening connecting said chambers, intake means and outlet means connected to said valve chamber, a two-part valve slideable in said valve chamber by pressures in said intake means and measuring chamber and having one part exposed to said pressure opening and controlling said outlet means and the other part exposed to said intake means and controlling said intake port, a spring between said parts tending normally to move them to closing position, and a check valve mounted in said port and adapted to close in the direction from the measuring chamber to the valve chamber.

4. In a measuring valve, a body formed to provide a measuring chamber and a valve chamber with a partition therebetween, said partition having an intake port connecting said chambers, intake means to said valve chamber and outlet means from said measuring chamber and having a portion in axial alignment with said valve chamber and in communication therewith, a valve slideable in said valve chamber by pressures in said intake means and measuring chamber and adapted to control said port and having one end adapted to seat against said aligned portion of said outlet means, and a check valve mounted in said port and adapted to close in the direction from the measuring chamber to the valve chamber.

5. In a measuring valve, a body formed to provide a measuring chamber and a valve chamber with a partition therebetween, said partition having an intake port connecting said chambers, intake means to said valve chamber and outlet means from said measuring chamber, a valve slideable in said valve chamber by pressures in said intake means and valve chamber and adapted to control flow through said port and outlet means, a piston slideable in said measuring chamber, said chamber having a fluid inlet for the introduction of fluid pressure to move said piston toward said outlet means, said fluid inlet and partition being disposed at opposite sides of said piston, and a check valve mounted in said port and adapted to close in the direction from the measuring chamber to the valve chamber.

6. In a measuring valve, a body formed to provide a measuring chamber and a valve chamber with a partition therebetween, said partition having an intake port connecting said chambers, intake means to said valve chamber and outlet means from said measuring chamber, a valve slideable in said valve chamber and adapted to control flow through said port and outlet means, a piston slideable in said measuring chamber, said chamber having a fluid inlet for the introduction of fluid pressure to move said piston toward said outlet means, said fluid inlet and partition being

said valve from covering said pressure opening.

7. In a measuring valve, a body formed to provide a measuring chamber and a valve chamber with a partition therebetween, said partition having an intake port and a pressure opening connecting said chambers, intake means and outlet means connected to said valve chamber, a valve slideable in said valve chamber and adapted to selectively obstruct said intake port and outlet means with respect to said intake means and pressure opening respectively, said valve being positioned between said opening and intake means, whereby it is moved in opposite directions respectively by the pressures in said opening and intake means, a piston slideable in said measuring chamber, said chamber having a fluid inlet for the introduction of fluid pressure to move said piston toward said outlet means, said fluid inlet and partition being disposed at opposite sides of said piston, and a check valve mounted in said port and adapted to close the same by gravity and to be moved to an open position by pressure in the direction from said valve chamber to said measuring chamber.

partition being disposed at opposite sides of said piston, a check valve mounted in said port and adapted to close in the direction from the measuring chamber to the valve chamber, and means preventing said valve from covering said pressure opening.

8. In a measuring valve, a body formed to provide a measuring chamber and a valve chamber with a partition therebetween, said partition having an intake port connecting said chambers, intake means to said valve chamber and outlet means from said measuring chamber, a valve slideable in said valve chamber by pressures in said intake means and measuring chamber and adapted to control said port and outlet means, a piston slideable in said measuring chamber, said chamber having a fluid inlet for the introduction of fluid pressure to move said piston toward said outlet means, said fluid inlet and partition being disposed at opposite sides of said piston, and a check valve mounted in said port and adapted to close the same by gravity and to be moved to an open position by pressure in the direction from said valve chamber to said measuring chamber.
